2,200,912

COLLAPSIBLE BEACH CHAIR AND COT

Alfred E. Brandon, New York, N. Y.

Application June 7, 1938, Serial No. 212,241

10 Claims. (CL 155—45)

This application is a continuation in part of application Serial No. 164,282; filed Sept. 17, 1937, Patent No. 2,148,898; dated Feb. 28, 1939.

This invention relates to chair of the collapsible type, used at beaches, pleasure resorts, deck or lawn or the like; and the objects are, in addition to those already stated in the above said application:

1. To provide a structure which affords quick adjustments and wherein the parts are unlikely to become disarranged.

2. To provide a collapsible beach chair and cot, wherein the back rest frame head end portion is supported free from the ground area when the chair is converted into a cot.

3. To make novel provision for forming the side rails of the back rest frame into arm rest portions, so that the user of the structure may be more comfortable when the back rest frame is below the main arm rests.

4. To provide a beach chair and cot wherein the supplemental leg frame and transverse brace frame facilitate shelving space which remain unobstructed by the back rest frame in any adjusted position the structure may be.

5. To provide an improved rack element on the supplemental leg frame to serve as shelf element at a higher elevation on the back rest frame and also as rack element in any position the structure is used.

6. To make novel provision for securing the fabric of the back rest and the inner end of the seat frame on the structure and which affords means for tightening of the fabric when it becomes too stretched especially in the center portions thereof.

Some of the objects of the invention having been stated, other objects, such as the structure affords an inclined area to rest on when it is in extended position as a cot and thus affords the occupant of same a forward vision with less effort, will appear as the description proceeds when taken in connection with the accompanying drawing, in which:

Fig. 1 is a side elevational view of the structure constructed according to the invention, in extended position as a cot.

Fig. 2 is a plan view of Fig. 1.

Fig. 3 is a sectional view along the line 3—3 of Fig. 2, but the rack element, within the boundaries of the leg frame, is in open position.

Fig. 4 is a sectional view substantially along the line 4—4 of Fig. 3.

Fig. 5 is the same structure as shown in Fig. 1, but in one of many positions when it is converted

into a chair and the back rest frame is below the arm rests. The dotted lines indicate another position of the leg frame on the rear legs of the structure.

Fig. 6 is the same as Fig. 1, but the same structure is shown in a position it assumes when the back rest frame is connected with the arm rests. The dotted lines indicate additional positions of the back rest frame and leg frame and also the position of the rack element when it is open. 10

Fig. 7 is an enlarged fragmentary sectional view along the lines 7—7 of Fig. 6.

Fig. 8 is an enlarged transversely sectional view at the junction of the fabric of the seat and back rest frame. 15

Referring more specially to the drawing, Figs. 1 to 8 give one form of the invention and wherein the numeral 1 indicates front legs, 2 rear legs. Arm rests are provided with upper portion 3 and lower portion 3a. 4 are link elements, 5 is a transverse brace frame, 6 is a seat frame, 7 a back rest frame with a leg frame 8 and an additional frame 9.

As shown, the legs 4 and 2 are positioned in alignment forwardly and rearwardly of the chair structure and their upper ends are pivoted to the portions 3a of the arm rests by rivets or bolts 10 and 11. Pivotedly connected with the upper end of the rear legs and rear end portion of the arm rests is the upper end portion of the link elements 4. 25

The front legs 1 are connected by a pair of bars 12 and 13, the rear legs by a pair of bars 14 and 15, and the link elements by a bar 16. The bars 12 and 16 are disposed at equal distance 35 from the arm rest portions 3a and, pivotally connected therewith are the side rails of the seat frame 6. It is obvious from the drawing that, the front end of the rails of the seat are against the inner side of the front legs and rear ends are against the outside of the link elements and are pivotally connected therewith in a manner so that the said side rails of the seat are at all times parallel and also in vertical alignment with the portions 3a of the arm rests, and the link elements are substantially parallel with the front legs. 40

The frame 5 is intended to be positioned in a manner different from that shown in my application Serial No. 164,282 (Patent No. 2,148,898) 50 when it is in engagement with the lower portions of the rear legs 2. Therefore I make this frame so that it will be at all times separated from the back rest frame and thus affords shelving space in any adjusted position of the structure. In this 55

form shown, the inner end of the brace frame 5 is pivoted to the lower end of the link elements 4 at 17 by screws or bolts, but it may be also connected by a cross bar if so desired, and the side 5 rails are provided with recesses 18 on the under-side and other recesses 19 on the outer end of the frame 5 for engagement with the cross bar 14 of the rear legs 2 to secure said legs in adjusted position. This frame 5 comprising end rails or 10 bars 20, 20a and, braces 21, 21 crossing each other and whose ends are disposed at the jointure of the side rails of the frame 5 and end bars 20, 20a. 22 are slats secured at the upper surface of the ends bars 20, 20a and braces 21, 21.

15 The inner end of the back rest frame 7 is pivoted on bar 16 and the upper or head end is provided with the usual bar 23 as shown in the drawing. The side rails of this back rest frame are so formed at 24 to provide a resting place for 20 the arms of the occupant, when the back rest frame is below the arm rests when the structure is extended in use either as a chair or as a cot. The end portion of this portion 24 is provided with means 25 which may be inclined in respect to the 25 side rails urging thereby the upper portion of the structure against the side rails of the back rest frame and engageable in recesses 26 spaced on the arm rest 3 in a manner so that the back rest frame is adjustably secured with the arm rests and the 30 portions 24 by their inclined ends 25 will prevent the sides of the structure from spreading open at the upper portion thereof. The back rest frame is also provided with recesses at 27 spaced on the rear side and these recesses are formed to 35 fit over cross bars 15 and adjustably secure the back rest frame to the said cross bar 15 and thereby uniting the rear legs with the front legs. It is obvious that, when the back rest frame is being swung further rearward, its positions at 40 said cross bar 15 will afford the free end portion of said leg frame to unite with the free end portion of said brace frame upon said cross bar 14. Thus, both said frames by their positions tend to 45 form braces which, being substantially vertical and opposed to each other, are extending from the lower portion of the rear legs to either ends of said back rest frame.

From Fig. 1 it is obvious that, the leg frame 8 functions to prevent the rear legs from spreading 50 rearwardly and to support the back rest frame when the structure is in the position shown. Also, in other adjusted positions, such as shown in Fig. 5, the leg frame 8 stabilizes the back rest frame when it is positioned as indicated by the dotted 55 lines in said figure. It will be noted that the lower connection at 28 which is in the form of recesses on the extreme end portion of the leg frame 8, is not on the bar 14 of the rear legs, but on the bar 20a of the frame 5; thus the free end of frame 60 5 is pressed down upon the bar 14 by the frame 8 and to produce increased stability to the structure. This frame 8 is adapted to be swung from the rear of the back rest frame about the pivotal connection to the front of the back rest when 65 the structure is collapsed. This frame 8, the upper ends of the side rails of which are pivoted to the bar 23 comprises a pair of cross bars 29, 29a which connect the side rails. 30 are dowels (as shown in Fig. 4) or slats (as shown in Fig. 7) 70 and they are disposed parallel with the side rails and their ends are secured at the bars 29, 29a. It is obvious, that the dowels or slats 30 as well as the slats 22 are preferably disposed so that they run longitudinally in respect to the device so 75 as to form a continuation in respect to one an-

other when the free end of the frame 8 and that of the frame 5 are engaging the cross bar 14; also that when both frames 5 and 8 are in said position the shelving space or area is increased and articles disposed thereon are prevented from falling therefrom and further, such articles need not be removed when the chair is converted into a cot. And the dowels or slats 30 are so disposed to produce rack facility which affords convenience for articles to be hung thereon at all adjusted 10 positions of the structure.

31 are plate elements, secured by screws or rivets 32 on the side rails of frame 8, to contact with the front of the side rails of the back rest frame and therewith stabilize the frame 8 in any 15 position with the back rest frame. These plate elements are of a length sufficient to form an inner and outer projection 31a and 31b on each side rail of the frame 8. Projection 31b is adapted to come in contact with the fore and rear side 20 of the side rails of frame 7 and thereby provides means for bracing the frame 8 in either open or closed condition when said frame 8 is swung about the jointure between the back rest frame 7 and leg frame 8; while the portion or projection 31a 25 contacts the side rails of another frame 9 and it serves to check the position of the frame 9 when in open and also closed positions, as is evident from the drawing.

The frame 9 serves as a shelf element which can 30 be reached conveniently by the user of the structure from over cross bar 23 and it affords a place for articles, which are preferably separated from the lower or bottom shelf element under the seat. One form of this frame 9 shows the side rails pivoted with the side rails of the leg frame 8 by rivets or bolts 33; the pivotal connections being adjacent bar 29, and cross bars 34 connect the side rails. 35 is a recess on each side rail disposed in a manner so to clear bar 29 whereby both frames 40 8 and 9 may come in alignment when it is desired to fold the frame 9 into closed position; and a catch may be provided to maintain the frame 9 in closed position and the catch (not shown) may be disposed on the side rail to co-operate with the 45 plate element 31 or with the bar 23.

In the seat and back rest frames of this form of the invention I use a fabric element 36 which is commonly employed in structures used on beaches. And in Fig. 8, is shown a novel manner whereby the fabric element can be tightened and held in proper condition especially when the fabric element becomes stretched after frequent use. The bar 16 is constructed so as to form two halves 37 of a length substantially the width of 55 the fabric 36 inner ends of which are inserted therebetween. Said inner ends, being of the seat and back rest, are secured by bolts 38 which tighten the halves of the bar 16 and the ends of the fabric element. The bolts are spaced on the 60 bar 16 in apertures having washers 39. The other end of the seat and back rest receive the fabric element, in the usual well known manner, on bars 12 and 23 respectively.

The panel of the frame 9 may be of wood or 65 of similar material as of the seat or back rest, but herein as shown said panel is constructed of a plurality of slats 40 which run parallel with the side rails of the frame 9.

The improved chair and cot, though light in 70 weight, is strong and durable and is extremely comfortable for the occupant, and is adjustable with practically little effort and gives positive safety as chair or cot to any size or weight of user, and affords shelving space which gives protection 75

and convenience for articles to be disposed of temporarily by the user of the structure or his or her friends.

In the drawing and specification there has been set forth a preferred embodiment of the invention, and although specific terms are employed, they are used in a generic and descriptive sense only, and not for purposes of limitation, the scope of the invention being set forth in the appended claims.

And I claim:

1. A combination beach chair and cot comprising arm rests, front and rear legs respectively pivoted to said arm rests, link elements pivotally mounted upon the pivots joining said arm rests to said rear legs and depending therefrom, pivotally connected seat and back rest frames pivoted to said depending links, the front end of the seat frame being pivoted to said front legs, cross bars connecting said rear legs, and recesses rearward in each side rail of said back rest frame adapted to engage one said cross bar whereby said back rest frame may be retained in various positions when detached from the arm rests, a brace frame movable below said seat frame being pivoted to the depending links and provided with means engageable with said rear legs so that said brace frame may remain unobstructed by the back rest frame when the structure is extended as a cot, a supplemental leg frame having one end pivotally mounted on the free end of the back rest frame, the other end adapted to be engaged with the said rear legs and recesses on the free end of said supplemental legs engaging another one of said cross bars when the back rest frame engages said first cross bar and the seat is in alignment therewith.

2. A combination beach chair and cot as in claim 1, means mounted upon the side rails of said supplemental leg frame to form lateral projections adapted to engage the side rails of said back rest frame whereby said supplemental leg frame may be braced in open or closed condition when said back rest frame engages the said arm rests.

3. A combination beach chair and cot comprising arm rests, front and rear legs respectively pivoted to said arm rests, link elements pivotally mounted upon the pivots joining said arm rests to said rear legs and depending therefrom, a seat frame pivoted to said front legs and to said depending links, a back rest frame, supplemental arm rests forming projections on each of the side rails of said back rest frame, and cooperative locking means between said arm rests and end portions of said projections whereby the back rest frame is adjustable upon said arm rests, a cross bar connecting said rear legs, and means on the side rails of said back rest frame adapted to be positioned upon said cross bar whereby said back rest frame may be retained in many adjusted positions either as a chair or a cot, a leg frame having one end pivotally mounted upon the head end of the back rest frame, a brace frame having one end pivotally mounted upon said depending links, another cross bar connecting the lower portions of said rear legs, and locking means at the end portions of the free ends of both said frames adapted to unite upon the latter cross bar, whereby said back rest frame may be secured in various inclined positions or in substantially horizontal position in alignment with said seat frame to form a cot with said seat frame.

4. A combination beach chair and cot as in claim 1 with the addition of another frame piv-

oted upon the side rails of said supplemental leg frame, said frame normally in alignment with the side rails of said supplemental leg frame having a plurality of spaced bars connecting the pivoted sides thereof to form racks, and a plate element mounted upon either side rail of said supplemental leg frame adapted to engage the side rails of said other frame and also the side rails of said back rest frame whereby to limit movement of said rack frame and also of said supplemental leg frame when both said frames are swung about their pivots independently of each other.

5. A combination beach chair and cot as in claim 1 with the addition of means to secure the ends of a fabric element upon the pivot joining said seat and back rest frames, said means comprising a longitudinal slot in said pivot engageable by said ends of the fabric element, a plurality of apertures spaced in said pivot and, means engaging said apertures adapted to clamp said ends of the fabric element between the interior of said slot so that the ends of the fabric may be adjustably secured against misplacement at the said pivot of said seat and back rest frames.

6. A combination beach chair and cot comprising arm rests, front and rear legs respectively pivoted to said arm rests, links pivotally mounted upon the pivots joining said arm rests to said rear legs and depending therefrom, pivotally connected seat and back rest frames pivoted to said depending links, lateral recesses on each side rail of said back rest frame forming projections for said back rest frame, and recesses in said arm rests engageable by said projections capable to hold the back rest frame upon the arm rests against misplacement in its various positions, other recesses on the side rails of said back rest frame, and a cross bar connecting said rear legs engageable by said latter recesses when the back rest frame is moved further rearwardly and from said arm rests whereby said back rest frame may be secured in various inclined positions or in substantially horizontal position in alignment with said seat frame to form a cot with said seat frame and, the said projections serving then as arm rests.

7. A combination beach chair and cot as in claim 6, a leg frame having side rails each of which having one end pivotally mounted upon the free end of said back rest frame and, means provided at their other or opposed ends adapted to be in engagement with the lower portion of said rear legs when said back rest frame is in substantially horizontal position in alignment with said seat frame to form a cot with said seat frame.

8. A combination beach chair and cot as in claim 6, a pair of legs pivotally mounted upon the head end of said back rest frame normally extending toward the lower portion of said rear legs, means provided at each free end of said first named legs mountable upon said lower portions whereby said first named pair of legs may be positioned so as to brace the head end of said back rest frame to the lower portion of said last named rear legs, and a frame pivotally connected to said first named pair of legs so that said frame may be positioned in alignment with said first named pair of legs or in divergent positions in respect thereto when said back rest frame is in any inclined position or in substantially horizontal position in alignment with said seat frame to form a cot with said seat frame.

9. A combination beach chair and cot as in claim 3 with the addition of plate elements mounted upon the side rails of said leg frame,

said plate elements each having means engageable with the respective side rails of said back rest frame whereby said leg frame may be braced when said back rest frame engages said arm rests or is positioned upon said cross bar.

10. A combination beach chair and cot comprising arm rests, front and rear legs respectively pivoted to said arm rests, link elements pivotally mounted upon the pivots joining said arm rests to said rear legs and depending therefrom, pivotally connected seat and back rest frames pivotally connected to said depending links, a cross bar adjacent said arm rests connecting the said rear legs, cooperative locking means between each side rail of said back rest frame and said cross bar adaptable to hold the back rest frame so that said back rest frame may be positioned in various

inclined positions upon said cross bar and also to secure thereon said back rest frame in substantially horizontal position in alignment with said seat frame to form a cot with said seat frame, a frame pivotally mounted upon the head end of said back rest frame carrying means to engage the side rails of said back rest frame, said means adapted to be placed on either side of the rails of said back rest frame and arranged so that when said frame swinging about its pivot is positioned forwardly in respect to the device, said frame may be braced substantially in alignment with said back rest frame and when said frame is being positioned rearwardly, said frame is braced in a divergent position to the best rest frame.

ALFRED E. BRANDON.
